UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

UNCOUPLING DEVICE.

Application filed October 13, 1926. Serial No. 141,319.

My invention relates to an uncoupling device for actuating the locking mechanism of a car coupler so as to cause it to assume the positions necessary for unlocking and opening the knuckle.

Car couplers in common use at the present time are usually constructed with a lock lifter or actuating member which, in addition to serving as a means for moving the lock to unlocked position, also perform the function of a lock-to-the-lock for preventing the locking block by which outward rotation of the knuckle is restrained from accidentally moving to unlocked position as a result of the blows and jars incident to service. While such lock-to-the-lock means is generally satisfactory, particularly where the speed of the trains is moderate, it is the object of my invention to provide improved means for preventing the coupler lock from accidentally moving to unlocked position, such improved means being capable of employment in conjunction with means designed for that purpose now in use and when associated with the latter serving to supplement the same so as to overcome any defect of operation thereof.

The primary feature of the invention consists in constructing the uncoupling device as an uncoupling lever formed of a plurality of relatively movable lever members, one of the lever members being adapted to actuate another to cause the latter to perform an uncoupling movement, and means being provided for preventing the last named lever member from accidentally moving to uncoupling position until after the member by which it is actuated has executed a preliminary movement toward uncoupling position.

A further feature of the invention consists in constructing the device with an uncoupling lever comprising relatively movable lever arm members which are capable of changing their angular relations, means being provided for movably mounting the uncoupling lever on a car body, and the said lever arm members being operatively coupled so that neither is capable of assuming uncoupling position independently of the other. A more specific feature of the invention consists in forming the uncoupling device with a transversely extending uncoupling lever comprising an outer rotatable member and an inner rotatable mem-

ber relatively movable thereto and adapted to be actuated thereby, and in associating therewith means for preventing the inner end of the inner member from moving upwardly independently of a downward rotation of the outer end of the outer member.

Further features of the invention pertaining to advantageous structural details and combinations of parts will hereinafter appear and be pointed out in the claims.

In the drawings illustrating a preferred embodiment of the invention,—

Figure 1 is a plan view of an uncoupling device embodying the invention, showing its relation to the end of a car, the parts being in locked position.

Figure 2 is an elevational view of the construction shown in Fig. 1, also showing the parts in locked position.

Figure 3 is a detail elevational view of a portion of the mechanism, the parts being in locked position and a portion of the outer uncoupling lever member being broken away.

Figure 4 is a view corresponding to Fig. 2, but showing the positions assumed by the parts when the coupler locking mechanism is in lock-set position permitting the knuckle to be subsequently opened.

Figure 5 is an elevational view showing the relation the parts assume when the device is actuated for throwing the knuckle open, this relation of the parts also being that which obtains before the downward force applied to the outer end of the outer lever arm is released in the act of setting the lock in lock-set position.

Figure 6 is a detail sectional view on the line 6—6 Fig. 1.

Figure 7 is a detail plan view of the uncoupling lever fulcrum bracket.

Figure 8 is a detail elevational view of the fulcrum bracket.

Figure 9 is a detail plan view of the outer end of the inner uncoupling lever member.

Figure 10 is a detail elevation of the outer end of the inner uncoupling member.

The car coupler 1 illustrated in the drawings is of the well known standard D-type wherein the locking block is actuated by a lock lifter 2 which extends upwardly through the top of the coupler head for connection to the uncoupling device. When in normal locked position this lock lifter 2 operates with the coupler head so as to pre-

vent the locking block from accidentally moving upward to unlocked position.

The uncoupling device for actuating the coupler locking mechanism involves a transversely extending lever fulcrumed upon a bracket 3 which is rigidly mounted on the car body, the said lever comprising an outer member 4 and an inner member 5. These lever members overlap adjacent the fulcrum bracket 3 and their neighboring ends are preferably flexibly connected by a link 6, which may advantageously be secured to the lever members by rivets 7 and 8, respectively.

15 The inner end 9 of the inner lever member is preferably of round cross section and extends through the eye of the lock lifter 2 sufficiently to accommodate the movements of the coupler. The outer end of this lever member 5 is fashioned with a shouldered opening or recess 10 into which portions of the fulcrum bracket 3 project. At its upper end the recess in the member 5 is constricted, as indicated at 11, to receive a locking lug 12 carried by the bracket. It will be seen that this lug by cooperating with the inner lever member 5, prevents the latter from executing an uncoupling rotation until after it has moved upward sufficiently far to permit said lug to pass out of the constricted portion 11 of the opening in the inner lever member. At the lower end of the constricted portion 11 the recess 10 at the outer end of the inner lever member is shouldered as at 13 so that, as illustrated in Fig. 4, the outer end of the member 5 may be supported by resting upon the upper end of the locking lug 12 when the parts are in lock-set position. Toward its lower end the bracket receiving opening of the inner lever member is bounded by an inclined face or wall 14 adapted to cooperate with a lug or projection 15 which, like the locking lug 12, may conveniently be made integral with the fulcrum bracket 3. The lower end of the lug 15 is preferably rounded so as to form a pivotal point for the inner lever member 5 when the latter rotates as it moves to and from uncoupling position. The incline 14 by cooperating with the stationary lug 15 causes the inner uncoupling lever member 5 to be shifted laterally so as to position the shoulder 13 of the lever above the locking lug 12 after the inner lever member has been freed from the locking control of said lug. Inward movement of the lever member 5 with respect to the car may be conveniently effected by providing the bracket 3 with an upwardly extending lug 16 which overlaps the inner face of said lever member. Outer movement of the inner lever member is prevented by the other lever member 4, which lies outside of the member 5 and is pivotally secured to the bracket 3. This pivotal mounting of the outer lever member 4 is

preferably effected by forming the bracket with a pivot stud 17 on which the lever member is journaled. The member 4 may be conveniently retained in assembled relation to the bracket by means of a washer 18 and a bolt 19.

The outer lever member 4 of the uncoupling device is adapted to be actuated either by the hand or the foot. To limit its movement in an uncoupling direction the fulcrum bracket 3 is preferably provided with a forwardly projecting portion 20 which passes below the outer arm 4 of the uncoupling lever in outwardly spaced relation to the point of pivotal support of the latter. The stop thus formed acts directly on the outer arm of the outer lever member 4 and thereby serves to prevent excessive movement of this member in case of breakage of the inner member 5 or a disconnection of the inner arm from the lock lifter 2. It will be appreciated that excessive movement of the member 4 may result in injury to the trainman, especially if the uncoupling device is operated by his foot.

It will be appreciated that the link 6 connecting the inner and outer lever arms and located inwardly of the pivot casting, reduces the friction between the lever arms in the act of locking when the knuckle is moved to a closed or locked position; and it will also be perceived that the preferred form of the opening in the outer end of the inner lever member 5 and the body of the pivot or fulcrum casting 3 are such that no binding takes place at any part of the operation of uncoupling.

When the trainman presses down on the outer end of the outer uncoupling lever member 4 the link 6 which connects the lever members causes the outer end of the inner member 5 to move upwardly until said last named lever is released from the control of the locking lug 12. About this time the inclined surface 14 of the inner lever member comes into contact with the projection 15 of the fulcrum bracket, thereby causing the member 5 to shift laterally toward the outside of the car. By this means the upper end of the locking lug 12 and the shoulder 13 are caused to overlap for a considerable distance. During this lateral shifting of the inner member 5 it also performs an upward or uncoupling rotation as the inclined surface 14 travels along the projection 15 of the bracket 3. When the downward force applied to the outer end of the member 4 is released after the uncoupling member 5 has been moved sufficiently far to raise the coupler lock to unlocked position, the outer end of the inner lever member moves down until it rests upon and is supported by the locking lug 12 of the bracket, assuming the position illustrated in Fig. 4. If the downward movement of the outer end of the le-

ver member 4 is continued, the inner lever member 5 performs the further uncoupling rotation necessary to effect a knuckle opening operation of the coupler mechanism.

5 1 claim:—

1. An uncoupling device for actuating the locking mechanism of a car coupler, said device involving an uncoupling lever comprising a plurality of relatively movable members one of which is adapted to actuate another to cause the latter to perform an uncoupling movement, and means for preventing said last named lever member from accidentally moving to uncoupling position 10 until after the lever member by which it is actuated executes a movement toward uncoupling position.

2. An uncoupling device for actuating the locking mechanism of a car coupler, said device involving an uncoupling lever formed of a plurality of members which are movable with respect to each other so as to change their angular relation, one of said members being adapted to cause another to 20 actuate the coupler locking mechanism, and means releasable upon a change in the normal angular relation of said lever member for preventing said locking mechanism actuating members from accidentally moving 25 to uncoupled position.

3. An uncoupling device for actuating the locking mechanism of a car coupler, said device involving an operating arm and an operated arm, and means for preventing said 30 operated arm from accidentally assuming uncoupled position, said arms being relatively movable, and said operating arm being adapted to release said operated arm from the control of said means.

4. An uncoupling device for actuating the locking mechanism of a car coupler, said device involving a rotatable operating arm and an operated arm, said arms being independently movable and adapted to vary their angular relation to each other during an uncoupling operation, and means releasable by 45 said operating arm for preventing said operated arm from accidentally moving to uncoupling position.

5. An uncoupling device for actuating the locking mechanism of a car coupler, said device involving an uncoupling lever comprising an operating arm and an operated arm, means for pivotally mounting the operating arm on the car body, and means fixed 55 with respect to the first named means for preventing said operated arm from accidentally moving to uncoupling position, said arms being relatively movable and having overlapping portions adjacent said pivotal mounting means.

6. An uncoupling device for actuating the locking mechanism of a car coupler, said device involving an uncoupling lever comprising relatively movable inner and outer 65

lever arm members adapted to change their angular relation during uncoupling movement, means for movably mounting said uncoupling lever on a car, and means for operatively coupling said arms so as to prevent 70 the inner member from accidentally rotating toward uncoupling position.

7. An uncoupling device for actuating the locking mechanism of a car coupler, said device involving an uncoupling lever having 75 an outer rotatable member and an inner rotatable member, said members being relatively movable and the outer member being adapted upon performing an uncoupling rotation to induce a preliminary upward movement of the outer end of the inner member and a subsequent uncoupling rotation of the latter, means for movably mounting said lever members on the car body, and means for preventing an uncoupling rotation of 80 the inner member until after the latter has moved upwardly.

8. An uncoupling device for actuating the locking mechanism of a car coupler, said device involving an uncoupling lever comprising an outer rotatable member and an inner rotatable member, a link pivotally connecting said members for communicating movement from one to the other, and a fulcrum bracket on which one of said lever 90 members is pivotally mounted, said bracket being provided with means for cooperating with the other of said lever members to prevent the latter from accidentally assuming uncoupling position.

9. An uncoupling device for actuating the locking mechanism of a car coupler, said device involving an uncoupling lever comprising an outer rotatable member and an inner rotatable member relatively movable thereto, means for actuating said inner member upon an uncoupling movement of said outer member, and a fulcrum bracket on which the uncoupling lever is movably mounted, each of said lever members being rotatable with respect to said bracket about independent pivotal points and said inner member being slidable with respect to the bracket.

10. An uncoupling device for actuating the locking mechanism of a car coupler, said device involving an uncoupling lever comprising an outer lever member and an inner lever member which are relatively movable, said members having overlapping portions, means for causing the outer lever member to communicate an uncoupling movement to the inner lever member, and a fulcrum bracket upon which said uncoupling lever is movably mounted, said inner member being recessed at its inner end to receive the bracket, the bracket being provided with a lug extending into said recess for cooperating with the inner lever member to prevent an uncoupling rotation of the latter, and 115

said bracket also being provided with means for cooperating with the inner lever member to effect bodily shifting thereof when the latter is free to perform an uncoupling rotation.

11. An uncoupling device for actuating the locking mechanism of a car coupler, said device involving an uncoupling lever comprising an outer member and an inner member, one of the members being pivotally mounted upon the car and the other being slidably and rotatably movable with respect thereto, said slideable and rotatable member being formed with a shouldered opening,

15 and a bracket carried by the car and extending into the opening, said bracket being provided with means for preventing an uncoupling rotation of said last named lever member until after it has executed an upward bodily movement, and said bracket and last named lever member being adapted to cooperate so as to prevent the latter from assuming coupled relation with respect to the bracket while the locking mechanism of the car coupler is in unlocked position. 20 25

In testimony whereof I affix my signature.

WILLIAM KELSO.
